FUEL COMBUSTION

Gustaf Dalén and Gustaf Erik Björklund,
Lidingo, Sweden, assignors to Svenska Aktie-
bolaget Gasaccumulator, Stockholm, Sweden,
a corporation of Sweden

Application February 6, 1933, Serial No. 655,334.
Renewed December 29, 1938. In Sweden Feb-
ruary 13, 1932

4 Claims. (Cl. 158—53)

Our invention relates to combustion, and more particularly to combustion of hydrocarbon fuels, and still more particularly heavy hydrocarbons, such as what is commonly termed fuel oil. In 5 one phase, our invention relates to cook stoves and, more specifically, to stoves including heat-accumulating mass in the form of a large block of metal or the like.

The object of our invention is to provide a 10 reliable combustion apparatus for fuel oil or the like and particularly adapted for continuous burning at a relatively slow rate.

Further objects and the nature and advantages of our invention will become apparent from 15 a consideration of the following specification considered in connection with the accompanying drawings illustrating the invention and forming a part of this specification, and of which:

Fig. 1 is a vertical, cross-sectional view of a 20 cook stove embodying the invention;

Fig. 2 is a cross-sectional view showing, in detail, one form of combustion apparatus usable in the cook stove of Fig. 1;

Fig. 3 is a cross-sectional view of a combustion 25 apparatus constituting a modification of the structure shown in Fig. 2.

Liquid hydrocarbon fuel or fuel oil, for example, the kind supplied generally for house heating, herein generally termed oil, is supplied to the 30 stove of Fig. 1 by means of the pipe or conduit 1. This pipe is connected to and discharges into a vaporizer 2, the detailed structure of which is shown in Fig. 2. In the vaporizer, the oil is converted to vapor form. The vaporizer is in 35 direct heat transfer relation with a large mass of metal 3, which serves for the accumulation of heat. The vaporizer 2 should be so intimately associated with the accumulating mass 3 that they are at the same, or substantially the same, 40 temperature. The accumulating mass 3 may be made of cast-iron or a cast-steel alloy. The vaporizer is maintained at so high a temperature that the oil is vaporized substantially instantaneously upon its introduction therein. We 45 contemplate the operation of our stove at high temperature, for example, 900° F.

From the vaporizer 2, the vaporized oil passes to a mixer 4 supplied with fresh air by means of a pipe or conduit 5. Pipe 5 is connected to 50 the surrounding atmosphere and the air passing therethrough may be preheated before reaching the mixer 4. The extent of preheating may be determined by the extent of the pipe 5 within the insulation. The vapor and air mixed therewith 55 are then fed through pipe or conduit 6 to the

burner 7, where the combustible mixture is ignited.

The gases or products of combustion in the channel or combustion zone 8 give up their heat to the accumulating mass 3 and thence pass 5 through the off-take or channel 9 to the chimney or flue 10. The upper surface 11 of the accumulating mass 3 is horizontal and flat and constitutes a cooking surface or hot-plate surface. The accumulating mass is surrounded by a thick 10 bed, preferably several inches thick, of insulation such as asbestos mixed with kieselguhr, and preferably a sheet metal cover is placed around the insulation. A well-insulated cover 12 is preferably provided which is hinged to the top of the 15 stove and folds down to cover the cooking surface 11. The stove may be provided with several cooking surfaces and may be provided with a high temperature oven in direct heat-transmitting relation with the accumulating mass or a 20 low temperature oven receiving heat essentially through insulation or both, as is illustrated in U. S. Patent No. 1,862,009, granted June 7, 1932, to Gustaf Dalén.

Referring more particularly to Fig. 2, the lower 25 end of pipe 1 is shown as providing a fuel feeding member having the shape of a nozzle 17 the opening of which is downwardly directed so as to allow the liquid fuel to drip therefrom in drops in free falling condition. The oil drops from the 30 tip of nozzle 17 onto a hot surface 18 at the bottom of the vaporizer 2 and in the main or vaporizing chamber 2a thereof. The vaporizer structure enclosing the chamber 2a is secured in good heat-conducting relation with the metal 35 mass 3 as by being bolted thereto on a smooth surface 19. This connection is made to the lower part of the heat-accumulating mass which is adjacent the burner 7. We call the surface 18 a hot surface because, in operation, it is heated 40 to a very high temperature due to the direct heat transfer relation with the wall structure of the combustion zone. Due to the suction produced by the hot gases leaving the combustion zone 8 through the stack or chimney, gases are drawn 45 from the channel 6 into the combustion zone 8. This in turn draws fresh air in through the pipe 5 to the mixer 4 and draws the vaporized oil into the mixer from the vaporizer 2. The mixer 4 is formed in the shape of a contracting and expanding nozzle with a slit 20 between the contracting and expanding parts, and the fresh air from the conduit 5 enters the contracting part of the nozzle and the vaporized oil from the vaporizer 2 enters the mixer through the slit 20.

Gas of such quantity or nature as to be essentially inactive with respect to combustion of oil vapor is supplied to the upper part of auxiliary chamber 24 of the vaporizer surrounding the drip nozzle 17 by means of conduit 15. The pipe 15 is connected to a chamber 14 which may be embedded in the insulation and which we will term a cooler. The chamber 14 is connected by means of a pipe 13 with the off-take 9 to receive products of combustion therefrom, and is also connected by means of the small diameter pipe 26 to atmosphere. The essentially inactive gas thus constitutes products of combustion with which are mixed a relatively small quantity of air which provides in the mixture delivered to the pipe 15 an extremely small percentage of oxygen. The chamber 14 is surrounded by a cooling water jacket 22 to which cooling water is supplied by pipe 21 and from which cooling water leaves 20 through pipe 23.

The drops of oil fall freely under the influence of gravity alone from the tip of nozzle 17 onto the surface 18 in the vaporizer. It will be understood from the above description that this surface 18 is extremely hot since it is in direct heat-transmitting relation with the high temperature metal mass 3. Consequently, the oil is very rapidly vaporized as soon as it hits this surface 18. Small quantities of coke are formed 30 at 18 as indicated in Fig. 2 and the oil falls onto the small mound of coke rather than directly onto the vaporizer surface, wherefore the surface of the coke may be said to constitute the surface 18. On account of the high temperature of the 35 vaporizer, this coke will be red hot or practically so.

By introducing a small amount of oxygen into the gas passing through pipe 15, the coke at 18 can be consumed. The amount of oxygen supplied by means of the gas mixture admitted through conduit 15 is preferably sufficient only to consume the coke and not sufficient to cause pre-ignition or at least to cause very little pre-ignition of the vaporized oil in the vaporizer 40 ahead of the mixer. In view of the high temperature of the coke and the temperature and quality of the vapor, the coke will be combusted before the oxygen effects any ignition of oil vapor.

It is one of the objects of the present invention 50 to prevent the vaporization of oil until it strikes the extremely hot surface 18. Gradual vaporization in any path of flow is extremely undesirable, as the light hydrocarbons are first vaporized and then the heavy hydrocarbons are vaporized more 55 gradually. In previous devices there has been difficulty due to this gradual vaporization in a pipe-like conduit and there has resulted slow moving, heavy hydrocarbons which have been partially turned into coke before the oil has 60 reached the place of vaporization. This has a tendency to choke the conduit or part referred to, a condition which has been a source of great difficulty. In accordance with the present invention, as the oil is supplied to the vaporizer from 65 the nozzle 17 which is maintained at a relatively low temperature, vaporization is prevented from taking place until the moment when the oil touches the vaporization surface. The latter is kept at such high temperature that even the 70 pitch-like particles of oil are vaporized. There remain only thin layers of coke, which can be disposed of by the supply of what we have termed the essentially inactive gas above referred to.

Furthermore, on account of the rapid vaporization, the vaporized oil acquires so high a tem-

perature, while maintaining low pressure, that its viscosity diminishes considerably. This, however, involves both advantages and disadvantages. The high temperature, as used by us in this stove, exceeds that of the flash-point of the oil and thus would cause immediate ignition of the gas in the vaporizer if there were sufficient oxygen in it. On the other hand, the reduced viscosity and consequent ready flow of gas tends to make the oil vapor mix very well with foreign additional 10 gases in order to form a homogeneous gas mixture. The difficulties in obtaining a homogeneous gas mixture have been recognized for a long time. At lower temperature, the oil vapors do not flow smoothly and are little inclined to mix with air. 15 Consequently, the mixture which is burned as a rule includes oxygen-free, cloud formations of oil vapors. These burn imperfectly and are the cause of soot collection.

In the present case, the disadvantages are overcome by the conveying to the vaporizer of the above described inactive gas containing a small amount of free oxygen. It is important that the inactive gas carry into the vaporizer oxygen only of such small quantities or proportions that no, or substantially no, ignition of the vaporized oil can take place in the vaporizer. The low quantity of oxygen contained in the mixed gas thus prevents ignition. On the other hand, due to the dilution, the flash point of the mixed gas rises 30 so that it can be mixed with fresh air in a chamber separate and communicating with the vaporizer, namely, the mixer 4, without risk of pre-ignition.

Furthermore, the inactive gas is preferably introduced adjacent the drip point of the nozzle and directed toward the hot or vaporization surface in the same direction as the dropping liquid oil, that is, downwardly through the auxiliary chamber 24. Thus, the inactive gas constitutes 40 an envelope for, or enshrouds, the dripping oil and prevents vaporization until the oil strikes the hot surface and furthermore prevents any tendency for vaporized oil to back up into the oil supply pipe and cause cracking or distillation before the oil reaches the vaporizer. It may be said that this inactive gas is an insulator for the oil supplied to the vaporizer.

Preferably, the distance of fall of the oil from the nozzle 17 to the hot surface 18 is relatively 50 small, for example, two or three inches.

The gas which we have termed essentially inactive gas, is cold, and thus will cool the nozzle 17 and the oil supply conduit leading up to the nozzle. If these parts are not cold, there 55 is likely to be pre-volatilization in them and, consequently, light hydrocarbons will flow as vapor and heavy hydrocarbons will flow slowly in the supply pipe or in the nozzle. This might result in dry-distillation giving off hydrogen and leaving 60 coke or other carbon in the pipe.

The essentially inactive gas flowing in the same direction as the drops of oil in the chamber 24 prevents any back-condensation. If this inactive gas is not introduced, oil vapor would fill the 65 whole vaporizer including the chamber 24 surrounding the nozzle. The walls of the chamber 2a are warmer than the vaporization temperature of the heavy hydrocarbons in the oil, and the nozzle is colder than the vaporization temperature of the light hydrocarbons. The danger, therefore, of formation of coke adjacent the nozzle is present and this danger is entirely eliminated by the introduction of the essentially inactive 70 gas moving in the same direction as the 75

dropping oil in the auxiliary chamber 24. This prevents condensation on the inside wall of chamber 24, which would result in such formation of coke. Thus, it is an important characteristic of our invention that the cold nozzle is heat-insulated from the hot vaporizer by means of moving inactive gas. Some diffusion of oil vapor into the essentially inactive gas will, of course, take place, but the auxiliary chamber 24 is narrow horizontally and the movement of the inactive gas is therefore (and due to the rate of supply) such that there is not sufficient time for oil vapor to diffuse through the stream of enshrouding fluid so that it might condense on the wall of chamber 24.

The mixture of oil vapor and dilution or inactive gas is drawn from the vaporizer into the injector or jet device 4 as above described. Although there is oxygen contained in the vapor in the vaporizer 2, the mixture thus formed is not a combustible mixture. It becomes a combustible mixture when the additional air is added thereto from the conduit 5. As above stated, the combustible mixture then passes through conduit 6 and to the burner 1. The quality of the mixture might be improved if conduit 6 contains means such as a spiral baffle indicated at 6a to cause turbulence and mixing of the combustible mixture. Preferably, a grid 27 is supplied subdividing the gas flow at the place of ignition. The conduit 6 (all the conduits are made of metal) is in heat-transmitting relation with the burner, whereas the burner is insulated from the wall structure of the combustion zone 8 by means of a ring 28 of asbestos or other heat-insulating material. This permits the heat of the burner to be dissipated through the pipe 6 and in this manner the temperature of the burner can be kept below the flash-point and thus spontaneous ignition of the gas under the grid 27 is avoided.

The vacuum obtained by the low specific weight of the gas column in the combustion zone 8 and the stack is utilized to draw in the fresh air through the pipe 5 so that it can mix with the gas mixture obtained from the vaporizer. The oil vapor is conveyed to the mixer 4 by means of injector action, which injector action produces a slight vacuum in the vaporizer. Due to this vacuum, the dilution gas mixture or essentially inactive gas is drawn from the off-take flue 9 through the pipe 13, cooler 14, and pipe 15 to the vaporizer 2. The cooling of the combustion gas in the cooler 14 increases the specific weight of the gas in the downflow leg of the circuit and thereby assists in producing the circulation of the combustion gas downwardly in pipe 15 and through the vaporizer and the conduit 6 and upwardly through the combustion zone.

The liquid fuel supply may be controlled automatically by a temperature-responsive element which may consist of a valve operated by a liquid-containing bulb of the usual type in heat-transmitting relation with the metal mass 3.

In Fig. 3 we propose to utilize excess of pressure for forcing the essentially inactive gas into the vaporizer. This we accomplish by placing a throttling device 29 in the off-take flue 9 and thus by excessive pressure the combustion gas is forced into the pipe 13, through cooler 14 and pipe 15 to the vaporizer. In this case we propose to cool the cooler 14 by air. It will be appreciated that if the throttling device 29 were not in the flue 9, and without injector action, the stack 75 would pull a vacuum up through the pipe 15 and

cooler 14 unless the cooler were sufficiently cool to offset this. The placing of the orifice plate 29 in the flue 9 permits downflow through parts 14 and 15 with air cooling.

Consequently, in the arrangement shown in Fig. 3, the mixer 4 need not take the form of an injector, although, however, in certain circumstances it might prove of advantage to do so. For the purpose of insuring proper mixture of the oil vapor supplied from chamber 2a with the air for combustion supplied through pipe 5, the mixer 4 in this embodiment is advantageously provided with a plurality of baffles 49 for causing tortuous and turbulent flow through the mixer. In this arrangement, fresh air cannot be added to the cooler 14 due to the existence of excess pressure. If required, an excess of oxygen in the dilution gases can readily be obtained by firing the stove with surplus of air so that all the air is not consumed in the combustion zone and some air passes downwardly through conduit 13. In the herein-before described embodiments of the invention showing the application thereof to a domestic cook stove of the heat accumulating type, the rate at which fuel is supplied in normal operation is such that it falls to the vaporizing surface in the form of drops. As will be readily understood, the invention may be applied to and is equally applicable to heating apparatus of such size that fuel must be supplied thereto in a continuously flowing stream rather than by separated drops.

It will be understood that the invention is not limited to the structures shown nor is our invention limited to accumulator type stoves, although there are special advantages in connection with the accumulating mass as maintaining at all times the desired very high temperature of the vaporizer.

The broad subject matter of the present invention is claimed in our co-pending continuation-in-part application Serial No. 166,916, filed October 2, 1937, the claimed subject matter in the present application being restricted to the features of species not disclosed in said continuation-in-part application.

What we claim is:

1. Liquid fuel combustion apparatus comprising wall structure forming a combustion zone, a vaporizer disposed in heat-receiving relationship to said wall structure and having a main chamber and an auxiliary chamber above and in communication with said main chamber, a liquid feeding member in said auxiliary chamber disposed to have liquid drop or pour therefrom into said main chamber, means to supply liquid hydrocarbon fuel to said feeding member, means to introduce into the upper part of said auxiliary chamber at a temperature relatively cool with respect to the temperature of said vaporizer, to have downward movement in the same direction as liquid falling from the feeding member, products of combustion from said combustion zone thereby forming with vapor of the hydrocarbon fuel a non-combustion supporting mixture in said main chamber, said auxiliary chamber being relatively narrow horizontally to provide sufficient flow of the gaseous fluid to prevent condensation on the wall thereof of vapor of the hydrocarbon fuel, a mixer, means to supply air to said mixer, means to conduct fluid from said main chamber to said mixer, and means to conduct fluid from said mixer to said combustion zone.

2. Liquid fuel combustion apparatus compris-

- ing wall structure forming a combustion zone and a metal heat-accumulating mass in heat-receiving relation with said combustion zone, a vaporizer disposed in heat-receiving relationship with said mass having a chamber, a liquid feeding member disposed to have liquid drop or pour therefrom into said chamber, means to supply liquid hydrocarbon fuel to said feeding member, an off-take flue leading from said combustion zone, 5 means to conduct products of combustion from said off-take flue to said vaporizer, means to cool the products of combustion so conducted, a mixer, means to supply fresh air to said mixer, means to conduct fluid from said vaporizer to 10 said mixer, and means to conduct fluid from said mixer to said combustion zone.
3. Liquid fuel combustion apparatus comprising wall structure forming a combustion zone, a vaporizer disposed in heat-receiving relationship 15 to said wall structure and having a vaporizing chamber, a liquid feeding member disposed to have liquid fall therefrom into said chamber, means to supply liquid hydrocarbon fuel to said feeding member, said vaporizing chamber having a hot surface vertically below said feeding member, means to introduce into said vaporizer to 20 enshroud the falling fuel an essentially inactive gaseous fluid containing products of combustion, the last mentioned means including a cooler for cooling said gaseous fluid to a temperature very much lower than the temperature of 25 said hot surface, means for withdrawing from the vaporizer the non-combustion supporting gas mixture of fuel vapor and gaseous fluid formed in

the vaporizer, and means for supplying combustion air to said non-combustion supporting gas mixture subsequent to its withdrawal from the vaporizer to provide a combustion supporting mixture for combustion in said combustion zone. 5

4. Liquid fuel combustion apparatus comprising wall structure forming a combustion zone, a vaporizer disposed in heat-receiving relationship to said wall structure and having a main chamber and an auxiliary chamber above said main chamber and in communication therewith, a liquid feeding member in said auxiliary chamber disposed to have liquid fall therefrom into said main chamber, means to supply liquid hydrocarbon fuel to said feeding member, said vaporizer having a hot surface in said main chamber vertically below said feeding member, means to introduce an essentially inactive gaseous fluid containing products of combustion into said auxiliary chamber to enshroud the falling fuel, the last mentioned means including a cooler for cooling said gaseous fluid to a temperature very much lower than that of said vaporizing surface, means for withdrawing from said main chamber the non-combustion supporting mixture formed in 25 said main chamber, and means for supplying combustion air to said non-combustion supporting gas mixture subsequent to its withdrawal from the main chamber to provide a combustion supporting mixture for combustion in said 30 combustion zone.

GUSTAF DALÉN.

GUSTAF ERIK BJÖRKLUND.
